RAILWAY TRUCK

Joseph A. Cameron, Montreal, Quebec, Canada,
assignor to The Symington-Gould Corporation,
Rochester, N. Y., a corporation of Maryland

Application November 13, 1933, Serial No. 697,852

14 Claims. (Cl. 105—208.2)

This invention relates to railway trucks and, more particularly, to means for connecting the lower portions of the side frames at opposite sides of said trucks.

5 The principal object of my invention, generally considered, is to provide the equivalent of a spring plank for connecting side frames of trucks, breakage at the ends of said spring plank acting member being avoided by articulated or 10 universal connections with said side frames.

Another object of my invention is the provision of means connecting either bolster spring supporting members or the tension member portions beneath bolster or window openings of side 15 frames, with the provision for articulation or universal movement at the points of connection to avoid breakage of said connecting means.

Other objects and advantages of the invention relating to the particular arrangement and 20 construction of the various parts will become apparent as the description proceeds.

Referring to the drawings illustrating my invention, the scope whereof is defined by the appended claims:—

25 Figure 1 is a fragmentary side elevational view of an end portion of a spring plank acting device or side frame connecting bar, an associated frame, bolster, bolster springs and spring plates being diagrammatically and fragmentarily illustrated.

30 Figure 2 is a fragmentary plan of the side frame connecting device shown in Figure 1, with portions of the frame and associated springs being diagrammatically illustrated.

35 Figure 3 is a fragmentary detail plan view of the side frame connecting device, as shown in Figure 2, but on an enlarged scale.

40 Figure 4 is a transverse sectional view on the line 4—4 of Figure 3, looking in the direction of the arrows.

45 Figure 5 is a plan view of the side frame connecting bar socket or intermediate member serving for attachment with a side frame or spring supporting plate thereof.

Figure 6 is an end elevational view of the socket shown in Figure 5.

Figure 7 is a side elevational view of the socket member shown in Figure 5.

50 Figure 8 is a horizontal sectional view of the socket member on the line 8—8 of Figure 7, looking in the direction of the arrows.

Figure 9 is a fragmentary view corresponding to Figure 1, but showing a modification.

55 Figure 10 is a fragmentary plan, partly in

horizontal section, of the form shown in Figure 9.

Figure 11 is a vertical sectional view on the line 11—11 of Figure 10, looking in the direction of the arrows.

Referring to the drawings in detail, like parts being designated by like reference characters, and first considering the embodiment of my invention illustrated in Figures 1 to 8, inclusive, there is diagrammatically shown a fragment of 10 a truck 1 comprising a side frame 2 having a tension member 3 and a window opening 4 above said tension member and receiving a bolster 5 and bolster springs 6 disposed between upper and lower spring plates 7 and 8, respectively. 15 In the present embodiment, the springs are shown as comprising an elliptic or leaf spring 9 and coil or helical springs 10.

The frame 2 is, in the present embodiment, of the type described and claimed in the Barrows 20 Patent No. 1,652,808, dated December 13, 1927, although I do not wish to be limited to this showing. Said frame, therefore, has diagonal reinforcing portions 11 which cut across the lower corners of the window opening for rigidifying the construction. Underlying the lower spring plate 8, in the present embodiment, is what may be termed a spring plank end member or spring supporting plate 12 which is desirably upwardly corrugated or embossed, as indicated at 13, to interlock with the diagonal reinforcements 11 on the frame, as will be understood. Other means for interlocking the plate 12 with the tension member 3 or upper web 14 thereof may be provided, if desired, in accordance with the usual practice.

The spring plank end member 12, or what might be termed the truck or side frame connecting bar adapter, has inwardly extending ears 15 spaced longitudinally of the frame 2 and provided with 40 depending apertured lugs 16 receiving a normally horizontal pivot pin 17 which, in turn, passes through a socket member or casting 18 for pivotally mounting said member between the ears 15. The socket member 18 has a receptacle or slot 19 45 which normally receives the end portion of the side frame tie member 20. Said tie member is desirably pivotally connected to the socket member 18 by means of a normally upright pivot pin 21 which intersects the pin 17 and is received in a corresponding cut-out portion 22 therein, whereby said pin 17 is retained in position without the use of auxiliary fastening means. The pin 21 may be prevented from undesired removal 50 55

or loss by means of a head 23 and a cotter 24 passing through the lower end portion where it projects below the socket casting 18.

Although only one side frame and the adjacent ends of the bolster and spring plank acting device are illustrated, it will be understood that the spring plank acting device desirably connects with a similar side frame in a similar manner at the opposite side of the truck.

Referring now to the embodiment of my invention illustrated in Figures 9, 10 and 11, there is diagrammatically shown a portion of a truck 1^a comprising a side frame 2^a having a tension member 3^a and a window opening 4^a above said tension member. Said window opening, as in the previous embodiment, is adapted to receive a bolster (not shown) and bolster springs 6^a which, in the present embodiment, are shown resting on a lower spring plate 8^a. As in the previous embodiment, the springs are shown as comprising an elliptic or leaf spring 9^a and coil or helical springs 10^a.

The truck 2^a, in the present embodiment, is of the double truss type as described in connection with the first embodiment, although I do not wish to be limited to this showing. Instead of having a spring plank end member or spring supporting plate, as in the preceding embodiment, the upper web 14^a of the tension member 3^a serves as this plate in addition to its usual function. In order to serve the purpose, said web 14^a is, in the present embodiment, formed with inwardly extending ears 15^a spaced longitudinally of the frame 2^a and provided with depending apertured lugs 16^a which may form continuations of the triangular gussets 25 at the inner side of the frame, said gussets reinforcing the connection between the portions of the web 14^a beyond the upright web portions 26 of the tension member and tying said extensions to said upright portions. As in the previous embodiment, the depending lugs 16^a receive a normally horizontal pivot pin 17^a which, in turn, passes through a socket member or casting 18^a which may correspond with the member 18 of the preceding embodiment, for the purpose of pivotally mounting said member between the ears 15^a.

The socket member 18^a has a receptacle or slot 19^a, as in the preceding embodiment, which normally receives the end portion of the side frame tie member 20^a which may correspond with the member 20 of the preceding embodiment. In the present embodiment, the tie member is pivotally connected to the socket member 18^a by means of a normally upright pivot pin 21^a which intersects the pin 17^a and is received in a corresponding cut-out portion 22^a therein. The pin 21^a may be headed, as indicated at 23^a, and prevented from undesired removal or loss by cotter or other retaining means 24^a.

Although only one side frame and the adjacent ends of the spring plank acting device or tie and associated parts are illustrated, it will be understood that the tie desirably connects with a similar side frame in a similar manner at the opposite side of the truck.

From the foregoing disclosure, it will be seen that I have devised a member for connecting the side frames at opposite sides of trucks, and particularly the spring supporting portions or tension members of said frames. It will also be clear that I have obviated the employment of the rigid, or substantially rigid, spring plank which has been employed to connect side frames at opposite sides of railway trucks and which sometimes breaks, particularly adjacent the places of con-

nexion with said side frames, and have substituted therefor a tie, as the connecting member or bar, which extends between the side frames and is articulated or universally connected thereto, thereby obviating strains due to relative movement of the frames in longitudinal or transverse planes, and consequent breakage and/or strains due to such movements, while at the same time providing adequate spacing means between the side frames, and particularly the tension members or spring supporting portions thereof.

Although preferred embodiments of my invention have been illustrated, it will be understood that modifications may be made within the spirit and scope of the appended claims.

I claim:—

1. In a railway truck, a side frame formed with a window opening, a spring supporting portion adjacent the lower part of said opening, and a bar for connecting said frame to an associated frame at the other side of the truck, said bar having a connection with said spring supporting portion comprising one pivot allowing horizontal articulation and another allowing vertical articulation.

2. In a railway truck, a side frame formed with a window opening the lower portion of which is defined by a tension member, a spring supporting plate resting on said tension member adjacent the lower portion of said window opening and interlocked with respect thereto, and a member for connecting said frame with an associated frame at the other side of the truck, said member being pivoted to an intermediate member about one axis and said intermediate member pivoted to the plate about an axis angularly disposed with respect to said first axis, so as to provide a universal connection with said plate.

3. In a railway truck, a side frame formed with a window opening the lower portion of which is defined by a tension member, said tension member having an upper web serving to support associated bolster springs, a bar for connecting said frame to an associated frame at the other side of the truck, and a connecting member intermediate said bar and web, said bar having a pivotal connection with said intermediate member about one axis, and the latter having a pivotal connection with the inner portion of said web.

4. In a railway truck, a side frame formed with a window opening, a spring supporting portion adjacent the lower part of said opening, said spring supporting portion having inwardly extending ears, a socket casting pivotally mounted between said ears about a normally horizontal axis, a member for connecting said frame with respect to an associated frame at the other side of the truck and having an end portion received in said socket casting, and means pivotally connecting said end portion to said casting about a normally upright axis.

5. In a railway truck, a side frame formed with a window opening, the lower portion of said window opening being defined by a tension member having an upper web, said web having inwardly extending ears spaced longitudinally of the frame, a socket casting pivotally mounted between said ears about a normally horizontal axis, a member for connecting said frame to an associated frame at the other side of the truck with an end portion received in said socket casting, and means pivotally connecting said end portion to said casting about a normally upright axis.

6. In a railway truck, a pair of side frames each formed with a window opening, a spring

supporting portion adjacent the lower part of each opening, and a member for connecting said frames, said member being connected to the spring supporting portion of one frame at one end 5 and the other frame at the other end, each connection comprising angularly related pivots for allowing universal angling.

7. In a railway truck, a side frame formed with a window opening, a spring-supporting portion 10 adjacent the lower part of said opening, and a bar for connecting said frame to an associated frame at the other side of the truck, said bar being pivoted to an intermediate member about a normally upright axis, and said intermediate member being 15 pivoted to said spring-supporting portion about a normally horizontal axis.

8. In a railway truck, a side frame formed with a window opening, the lower portion of which is defined by a tension member, a spring-supporting plate resting on said tension member adjacent the lower portion of said window opening and interlocked with respect thereto, and a member for connecting said frame with an associated frame at the other side of the truck, said member 25 being pivoted to an intermediate member about a normally upright axis, and said intermediate member being pivoted to said plate about a normally horizontal axis.

9. In a railway truck, a side frame formed with a window opening, the lower portion of which is defined by a tension member, said tension member having an upper web, serving to support associated bolster springs, and a member for connecting said frame to an associated frame at the other 30 side of the truck, said member being pivoted to an intermediate member about a normally upright axis, and said intermediate member being pivoted to said web about a normally horizontal axis.

40 10. In a railway truck, a pair of side frames, each formed with a window opening, the lower portion of each opening being defined by a tension portion, each tension portion supporting a spring plate interlocked therewith, and a member connecting said plates, the connection with each

plate comprising angularly related pivots for allowing universal angling between each plate and the adjacent end of said member.

11. In a railway truck, a pair of side frames, each formed with a window opening, the lower portion of each opening being defined by a tension member having an upper spring-supporting web, and a member for connecting said frames, said member being secured to each web by means of a connection comprising angularly related pivots for allowing universal adjusting movement therebetween. 5

12. In a railway truck, a pair of side frames, each formed with a window opening, a spring-supporting portion in each opening, a socket device connected to each of the adjacent parts of said spring-supporting portions, and a member with end portions connected to said socket devices, the connection between said member and socket devices comprising normally upright pivots, and the connection between said socket devices and spring-supporting portions comprising 15 normally horizontal pivots. 20

13. A socket casting for adjustably connecting a tie-bar to a side frame, comprising a receptacle 25 for an end portion of said bar, pivot apertures intersecting upper and lower walls of said receptacle, and pivot apertures intersecting portions of said member beneath said receptacle, the axis of said first-mentioned pivot apertures being 30 disposed at an angle to that of said second-mentioned pivot apertures.

14. In a railway truck, a side frame formed with a window opening, spring-supporting means involving an upper spring-supporting surface adjacent the lower portion of said opening, and a member for connecting said frame to an associated frame at the other side of the truck, said member having an upper surface normally disposed on the same level as said spring-supporting 35 surface, and universally articulated, by means including a normally horizontal pivot pin, with respect to said spring-supporting means. 40

JOSEPH A. CAMERON. 45
